UNITED STATES PATENT OFFICE.

WILLIAM CHARLES DIERKER, OF PEORIA, ILLINOIS, ASSIGNOR OF ONE-HALF TO
CHARLES THORNTON, OF PEORIA, ILLINOIS.

DESIGN FOR A CASING FOR SIGNALING DEVICE FOR VEHICLES.

Application filed March 4, 1922. Serial No. 1,018. Term of patent 3½ years.

To all whom it may concern:

Be it known that I, WILLIAM C. DIERKER, a citizen of the United States, residing at Peoria, in the county of Peoria and State of Illinois, have invented a new, original, and ornamental Design for Casing for Signaling Devices for Vehicles, of which the following is a specification, reference being had to the accompanying drawing, forming part hereof.

Figure 1 is a front elevation of a casing for signal device for vehicles showing my new design.

Figure 2 is a plan of the same, and Figure 3 is a rear elevation of the same.

I claim:

The ornamental design for the casing for a signaling device for vehicles as shown.

In testimony whereof I affix my signature in presence of two witnesses.

WILLIAM CHARLES DIERKER.

Witnesses:
